CLAIM

The ornamental design for a spa step, as shown and described.

DESCRIPTION

FIG. 1 is a perspective view of a first embodiment of a new design for a spa step;

FIG. 2 is a front view of FIG. 1.

FIG. 3 is a back view of FIG. 1.

FIG. 4 is a left side view of FIG. 1.

FIG. 5 is a right view of FIG. 1.

FIG. 6 is a top view FIG. 1.

FIG. 7 is a bottom view of FIG. 1.

FIG. 8 is another perspective view of FIG. 1.

FIG. 9 is a perspective view of a second embodiment of a new design for a spa step;

FIG. 10 is a front view of FIG. 9.

FIG. 11 is a back view of FIG. 9.

FIG. 12 is a left side view of FIG. 9.

FIG. 13 is a right view of FIG. 9.

FIG. 14 is a top view FIG. 9.

FIG. 15 is a bottom view of FIG. 9; and,

FIG. 16 is another perspective view of FIG. 9.

The evenly dashed broken lines show portions of the spa step and form no part of the claimed design.

1 Claim, 12 Drawing Sheets
